UNITED STATES PATENT OFFICE.

LEMMON M. BEELER AND FIELDING A. BEELER, OF NORFOLK, NEBRASKA.

DISPLAY-FIXTURE.

No. 848,623.

Specification of Letters Patent.

Patented April 2, 1907.

Application filed November 1, 1906. Serial No. 341,643.

To all whom it may concern:

Be it known that we, LEMMON M. BEELER and FIELDING A. BEELER, citizens of the United States, residing at Norfolk, in the 5 county of Madison and State of Nebraska, have invented certain new and useful Improvements in Display-Fixtures; and we do declare the following to be a full, clear, and exact description of the invention, such as 10 will enable others skilled in the art to which it appertains to make and use the same.

Our invention relates to improvements in display-fixtures, and more particularly to a revolving notion-rack for use in holding and 15 displaying cards containing various kinds of merchandise—such as buttons, buckles, beads, jewelry, safety-pins, &c.—also for holding or supporting small boxes, cartons, bottles, and similar articles.

20 The object of the invention is to provide a simple, practical, and inexpensive device of this character by means of which merchandise may be conveniently supported and effectively displayed.

25 With the above and other objects in view the invention consists in certain novel features of construction, combination, and arrangement of parts, as will be hereinafter described and claimed.

30 In the accompanying drawings, Figure 1 is a front elevation of the improved device. Fig. 2 is a sectional view on the line 2 2 of Fig. 1. Fig. 3 is a detail horizontal section on the line 3 3 of Fig. 1. Fig. 4 is an enlarged sectional detail illustrating the construction of the transverse bearing members and also showing a section of an adjustable shelf supported thereon. Fig. 5 is a perspective view of a portion of an adjustable shelf 35 illustrated in Fig. 4. Fig. 6 is a detail view illustrating modifications in the manner of sustaining the bearing members. Fig. 7 is a view similar to Fig. 4 and illustrating another modified form of a supporting-shelf. 40 Fig. 8 is a perspective view of a portion of the modified shelf illustrated in Fig. 7.

45 The improved device comprises a body portion 10 of any required size and preferably in a flat or plate-like form and mounted for rotation upon a stud 11, supported in a base 12.

50 Attached to the side edges of the body 10 are supporting members formed from strips of sheet metal 13 with the edges bent inwardly at opposite sides of the body to overhang the same and form ribs or flanges 14 15 parallel with the body and spaced therefrom.

The ribs or flanges are designed to support a plurality of holding devices for supporting the merchandise to be displayed (represented as a whole at 22) and formed by bending and 60 folding the longitudinal edges of a strip of sheet metal inwardly from opposite sides, as at 16 17, and then bending the remaining portions of the strips outwardly at reverse angles, as at 18 19, whereby longitudinal 65 channels 20 21 are formed in the opposite sides of the strip to provide supporting means for the edges of cards or similar devices upon which the goods to be displayed are mounted, as hereafter described.

70 At their ends the holding members 22 are provided with suitable means for coupling adjustably to the flanges 14 15, and in Figs. 1, 2, and 3 these holding means are shown in the form of clips 23, having recesses to engage the flanges 14 15 and secured in position by set-screws 24. By this means it will be obvious that the members 22 may be adjusted upon the flanges 14 15 to space their adjacent edges at any required distance 80 apart, and thus accommodate the other channels 20 21 to any required length of card or supporting member. The flanges 14 15 are preferably provided with spaced indicating-lines 25 26 to facilitate the adjustment 85 of the supporting members.

In Fig. 6 a modified means for attaching the members 22 to the flanges 14 15 is shown, consisting in providing each flange with a plurality of spaced apertures, as at 90 27, and providing the ends of the members 22 with perforated clips 28 and utilizing split rings, as at 29, to couple the member 22 with the flange. This construction may be employed to support some forms of merchandise. The members 22 are also authorized to support various forms of shelves or brackets upon which goods of certain kinds may be displayed, and these shelves may be employed instead of the adjustable cards 95 100 or any conjunction therewith, as may be preferred.

105 In Figs. 4 and 5 an approved form of an adjustable shelf is shown, consisting in a shelf member 30, having one edge 31 turned downwardly and adapted to be disposed between one of the members 22 and the body 10, and thereby supported in position, as represented in Fig. 4. The shelf member 30 is provided with lugs or clips extending 110 therefrom at the ends, one of the clips being shown at 32 and adapted to bear over the

ends of an extension-leaf 33, the extension-leaf having clips adapted to bear over the member 30 at the ends, one of the clips of the extension-leaf 33 being shown at 34. 5 The outer end of the extension member 33 is upturned, as at 35, to form a guard to the outer edge of the shelf. By this simple means it will be obvious that an adjustable shelf is produced which may be adjusted to any required width within the range of the holding-clips 32 34.

In Figs. 7 and 8 another modified supporting-shelf is shown, consisting in a leaf 36, having the inner edge turned downwardly, 15 as at 37, for bearing behind one of the supporting members 22 and with the outer edge turned upwardly and formed, preferably, into a series of engaging curves 38, the latter adapted to support combs and similar goods.

20 It will be obvious that the shelves 36 may be arranged in any desired form to accommodate different kinds of goods, such as bottles, cartons, and the like.

It will be obvious that a simply-constructed and convenient holding device is produced 25 adapted for use in retail stores of various kinds for displaying various kinds of goods, such as cards of buttons, safety-pins, buckles, jewelry, and the like, or bottles of perfumery, 30 toilet goods, and similar commodities.

Any number of supporting members 22 may be employed and spaced at any required distances apart and of any length.

Having thus described our invention, what 35 is claimed as new is—

1. A device of the class described comprising a body having spaced guide members at its side edges the edges of said members being bent in substantially parallel with the body, 40 holding members disposed transversely of said body, and means for adjustably connecting said holding members to the guide members.

2. A device of the class described comprising a body member, guide members at the side edges of said body, a plurality of supporting members having longitudinal channels in their opposite edges for supporting card-like structures, and means for adjustably coupling said supporting members to 45 said guide members.

3. A device of the class described comprising a body, guide members at the side edges of said body the edges of said members overhanging said body and at a distance therefrom, a plurality of supporting members, means for detachably coupling said supporting members to said guide members, a shelf-support having one edge turned downwardly for bearing between said supporting members and body. 55

4. A device of the class described comprising a body, guide members at the side edges of said body, a plurality of supporting members, means for detachably coupling said supporting members to said guide members, a shelf-support having one edge turned downwardly for bearing between said supporting members and body, and with guide-clips at the ends bearing over said shelf, an extension-shelf member bearing beneath said guide-clips and with clips at the ends bearing beneath said shelf member and with the outer edge of the adjustable shelf member turned upwardly to form a guard thereto. 60

5. A device of the class described comprising a body mounted for rotation, guide members at the side edges of said body, the edges of said members overhanging the opposite sides of said body, a plurality of supporting members having longitudinal channels, and means for adjustably coupling said supporting members at the opposite sides of said body. 65

6. A device of the class described comprising a body, guide members at the side edges of the body, a plurality of supporting members each formed from a strip of metal folded upon itself at the opposite edges and with the outer portions bent outwardly at reverse angles to form longitudinal channels in the opposite edges of said supporting members, and means for adjustably coupling said supporting members to said guide members. 70

In testimony whereof we have hereunto set 75 our hands in presence of two subscribing witnesses.

LEMMON M. BEELER.
FIELDING A. BEELER.
